UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

ROCK-DRILLING MACHINE.

1,088,984.

Specification of Letters Patent.

Patented Mar. 3, 1914.

Application filed September 9, 1910. Serial No. 581,197.

To all whom it may concern:

Be it known that I, CHARLES C. HANSEN, a citizen of the United States, and resident of Easton, in the county of Northampton 5 and State of Pennsylvania, have invented new and useful Improvements in Rock-Drilling Machines, of which the following is a specification.

This invention relates to that class of rock 10 drilling machines in which a suitable support, such, for instance, as a wagon, is provided with a frame uprising therefrom, along which frame a rock drill or other tool is movable toward and away from its work.

15 The object of this present invention is to provide means for positively moving the tool toward and away from its work by the medium of a suitable motor, means also being provided for exerting a tension on the tool 20 tending to hold it firmly against its work.

By the provision of the proper means for carrying out the above objects, the use of weights for feeding the tool to its work is obviated.

25 In the accompanying drawings, Figure 1 is a front view of one form of rock drilling machine with my improvement applied thereto, Fig. 2 is a side view of the same, partly in section, Fig. 3 is a top plan view 30 of the form shown in Figs. 1 and 2, and Fig. 4 is a partial side view of a modified form in which a turntable is provided for carrying the drill frame.

Proceeding to describe the form shown in 35 Figs. 1, 2 and 3, the wagon frame is denoted by 1 and its pairs of traction wheels by 2 and 3.

40 A suitable reversing engine 4 is provided for propelling the wagon in either direction, the driving connection between the engine and the pair of traction wheels 3 comprising a gear 5, pinion 6, sprocket wheels 7, 8, 9, 10, their chains 11, 12, and the gear and pinion connection 13, 14. Power is supplied to the engine 4 through the pipe 15 from any suitable source of power, not shown herein.

50 A drill frame uprises from the wagon frame 1, the upright members of which frame are denoted by 16, between which the rock drill 17 is fitted to slide toward and away from its work.

55 This rock drill is positively moved toward and away from its work by providing a feeding cable 18 and a withdrawing cable 19,

both leading to a winding drum 20 operated, in the present instance, by the engine 4, the cables being so led that as one is wound on the winding drum, the other will be unwound therefrom. The cable 18 leads downwardly along the side members 16 of the drill frame and passes under a fixed pulley 21, thence over a pulley 22 of a tension device and from thence under a fixed pulley 23 from which it passes to the winding drum 20.

Tension is applied to the feeding cable 18 to take up all slack thereon and to hold the rock drill firmly to its work. This is accomplished, in the present instance, by mounting 70 the pulley 22 on the end of a piston 24 operating in a cylinder 25 to which pressure fluid is fed through a pipe 26 leading to a source of pressure fluid supply, not shown herein.

75 The withdrawing cable 19 leads upwardly from the rock drill along the side members 16 of the frame and passes around a fixed pulley 27, from thence it passes downwardly to the winding drum 20.

80 A windlass 28 is shown on the frame for controlling the movements of a lifting cable 29 which passes upwardly around a fixed pulley 30, thence downwardly to a suitable point for attachment to the drill steel 31 for 85 handling the same.

A branch pipe 32 leads from the motive fluid pipe 26 to the windlass 28.

85 A branch pipe 33 leads from the pipe 32 to the rock drill 17 for supplying the motive fluid thereto.

In the form shown in Fig. 4, a turntable 34 is mounted on a track 35 carried by the wagon and the drill frame uprises from this turntable. Suitable clamps 36 are provided 90 for securing the turntable in its different positions. Suitable pulleys 37, 38, 39, may be provided for feeding the cables 18 and 19 through the center of the turntable and from thence back to the drum 20. In other 100 respects the parts of the machine are quite similar to those already described in connection with the form shown in Figs. 1, 2 and 3.

105 While I have chosen to show and describe my invention in connection with a rock drill, it is obvious that a tool of any character might be used without departing from the scope of the invention.

110 It is also evident that changes might be resorted to in the form, construction and

arrangement of the several parts without departing from the spirit and scope of my invention; hence I do not wish to limit myself strictly to the structure herein set forth,
5 but

What I claim is:

1. A wagon, a frame carried thereby, a percussive tool movable along the frame, an engine carried by the wagon, flexible connections between the engine and tool whereby the tool is moved positively along the frame toward and away from its work and means for operating the tool.
- 10 2. A wagon, a turntable thereon, a frame uprising from the turntable, a percussive tool movable along the frame, an engine carried by the wagon, flexible connections between the engine and tool whereby the tool is moved positively along the frame toward and away from its work and means for operating the tool.
- 15 3. A wagon, a frame carried thereby, a percussive tool movable along the frame, an engine carried by the wagon, flexible connections between the engine and tool whereby the tool is moved positively along the frame toward and away from its work and means for operating the tool.
- 20 25

frame toward and away from its work, a tension device engaging the flexible connection which operates to move the tool toward its work and means for operating the tool.

4. A suitable support, a frame carried thereby, a percussive tool movable along the frame, means for positively feeding and withdrawing the tool along the frame, a tension device for the feeding means and means for operating the tool.

5. A suitable support, a frame carried thereby, a percussive tool movable along the frame, tool feeding and withdrawing cables, means for operating them, a tension device engaging the feeding cable, and means for operating the tool.

In testimony, that I claim the foregoing as my invention, I have signed my name in presence of two witnesses, this first day of September, 1910.

CHARLES C. HANSEN.
